DESK PEDESTAL OR SIMILAR ARTICLE

Lawrence E. Blazey, Bay Village, and Paul Vignos, Canton, Ohio, assignors to Republic Steel Corporation, Cleveland, Ohio, a corporation of New Jersey

Application October 3, 1950, Serial No. 12,435

Term of patent 14 years

(Cl. D33—7)

To all whom it may concern:

Be it known that we, Lawrence E. Blazey and Paul Vignos, citizens of the United States of America, residing in Bay Village, in the county of Cuyahoga and State of Ohio, and Canton, in the county of Stark and State of Ohio, respectively, have invented a new, original, and ornamental Design for a Desk Pedestal or Similar Article, of which the following is a specification, reference being had to the accompanying drawing, forming a part thereof, wherein:

Fig. 1 is a front elevational view of a desk pedestal, embodying our new design;

Fig. 2 is a side elevational view;

Fig. 3 is a bottom plan view thereof, as seen from the underside of Figs. 1 and 2; and

Fig. 4 is a rear perspective view of the same.

The broken lines are only for illustrative purposes.

We claim:

The ornamental design for a desk pedestal or similar article, substantially as shown and described.

LAWRENCE E. BLAZEY.
PAUL VIGNOS.
